UNITED STATES PATENT OFFICE.

ISAAC DE MOTT, OF CANNONSVILLE, NEW YORK.

IMPROVEMENT IN HORSESHOES.

Specification forming part of Letters Patent No. **137,128**, dated March 25, 1873.

To all whom it may concern:

Be it known that I, ISAAC DE MOTT, of Cannonsville, Delaware county and State of New York, have invented a new and useful Improvement in Horseshoes, of which the following is a specification:

My object in this invention is to so construct the shoes of horses and oxen, and so attach the calks thereto, that the latter may be readily removed for sharpening or renewal without removing the shoe; and it consists in the manner of fastening the calks to the shoe.

I am aware that detachable calks have been made before, and that in themselves they possess no novelty as such; but the manner of fastening them to the shoe has hitherto been objectionable. Either the shoe has been weakened by the manner of fastening, or the calk is liable to become displaced by a lateral twist or strain.

In the accompanying drawing, Figure 1 is a view of the calk side of a horseshoe constructed according to my invention. Fig. 2 is a cross-section of Fig. 1 taken on the line *x x*. Fig. 3 is a view of one of the calks detached.

Similar letters of reference indicate corresponding parts.

A is the shoe. B is the toe-calk, and C C the heel-calks. D is a lip turned up from the shoe at the toe and heel, to which the calk is doweled, as seen in Fig. 2. These lips are turned so as to form angles with the face of

the shoe, and the calks are fitted to the angles and are doweled to the lips, while the other branch of the calk is fitted to the face of the shoe, and fastened thereto with a screw, E. F is the dowel. With the lip D a single dowel and a single screw is all that is required to hold the calk firmly to its place.

It will be noticed that but one hole is made in the shoe for each calk. The hole for the dowel-pin consequently does not weaken the shoe, but, placed as it is through the lip; and at a distance from the face of the shoe, it prevents the calk from tipping or twisting out of place much more effectually than when entering the shoe, as is usual with detachable calks. The lip D itself forms a very material support to the calk, keeping it in place and strengthening it.

The calks are made of hardened steel, and may be duplicated, so that new calks may be put on at any time without resorting to the blacksmith.

Having thus described my invention, I claim as new and desire to secure by Letters Patent—

A calk fastened to the shoe by a screw and supported by a lip and doweled thereto, substantially as shown and described.

ISAAC DE MOTT.
